UNITED STATES PATENT OFFICE.

R. PAUL HEMMING, OF PHILADELPHIA, PENNSYLVANIA, ASSIGNOR TO
GEORGE W. ENNIS & CO., OF SAME PLACE.

DESIGN FOR A RUG.

SPECIFICATION forming part of Design No. 16,148, dated July 7, 1885.

Application filed June 1, 1885. Term of patent 3½ years.

To all whom it may concern:

Be it known that I, RICHARD PAUL HEMMING, a citizen of the United States, residing at Philadelphia, in the county of Philadelphia and State of Pennsylvania, have invented and produced a new and original Design for a Rug; and I do hereby declare that the photographic print accompanying this specification conveys to any one skilled in the art a clear understanding of the same, and is sufficient to enable such persons to use my invention.

The leading features of my design consist in a center panel, A, showing foliated ornamentation. At the top of the center panel is the representation of a triple medallion, the center medallion showing the representation of a mountain-peak and a clouded sky in the background. This center panel, A, is also represented as partially inclosed by an ornamental molding, B. An outer panel is represented at D. The ground of this panel is represented as showing water, and is filled in with a number of fish having large heads and eyes. The lower corners of panel D are each ornamented by two medallions, which medallions run into the lower corners of the center panel, A. One of these medallions is ornamented by

the representation of a fish with large head and eyes. The other medallion has a floral ornamentation. The whole is surrounded by 30 the ornamental border E, as shown in the photographic print accompanying this specification.

The fishes shown in this design are after the Japanese order of ornamentation.

The photographic print illustrates and represents one half of the design or rug. The other half described, but not shown, is exactly like it.

What I claim as my invention is—

The design for a rug, consisting of a center 40 panel showing foliated ornamentation, and at the top a triple medallion, one showing the representation of a mountain-peak, at the lower corners two medallions, one ornamented by a representation of a fish; the other shows a 45 floral ornamentation; the center panel is surrounded by a panel showing water and fishes; the whole is surrounded by an ornamental border, as shown and described.

R. PAUL HEMMING.
